APPARATUS FOR FEEDING PLASTER BOARD
INTO A DRYING KILNCarl Absmeier, La Grange Park, Ill., assignor to
United States Gypsum Company, Chicago, Ill.,
a corporation of Illinois

Application September 29, 1928, Serial No. 309,172

5 Claims. (Cl. 198—21)

This invention relates to the method of feeding plaster board, wallboard or other sheets of material into drying kilns to remove the moisture in said material.

5 The invention further relates to a machine suitable for carrying out the above described method.

An object of this invention is to provide a method and machine for feeding plaster boards into drying kilns in which the drying kiln is located parallel to a setting conveyor where the plastic core of the plaster board is allowed to set, this arrangement of conveyor and drying kiln being adapted to conserve floor space in a factory.

15 Another object of the invention is to provide a feeding mechanism for a drying kiln in which the plaster board is fed into the drying kiln at different elevations or decks in order to provide a high capacity for the drying kiln.

20 A further object of the invention is to provide a kiln feed mechanism in which the direction of motion of the boards is automatically reversed to impel the board toward the kiln; also to improve methods of and machines for feeding sheets of material into drying kilns or other devices, in other respects hereinafter specified and claimed.

25 Reference is to be had to the accompanying drawings forming a part of this specification in which,

30 Fig. 1 is a diagrammatic side elevation of my improved kiln feed device, Fig. 2 is a side elevation of the improved kiln feed mechanism, Fig. 3 is a plan view of the kiln feed mechanism, Fig. 4 is a sectional view through the machine taken 35 on the line 4—4 of Fig. 2, Fig. 5 is a sectional view through the machine taken on the line 5—5 of Fig. 2, Fig. 6 is a detailed sectional plan view of a portion of the control mechanism, Fig. 7 is a fragmentary sectional elevation on a large scale, 40 of the driving mechanism, and Fig. 8 is a sectional elevation of the control cam.

45 The plaster board of commerce is usually composed of a pair of heavy paper sheets separated by a core of cementitious material such as gypsum. In the manufacture of this plaster board, the upper and lower sheets of paper are moved continuously while the gypsum stucco, mixed with water to form a plastic material, is introduced onto the lower sheet of paper, the upper sheet is applied and a roller rolls the material to the desired thickness of board. This specially prepared board with the cementitious material still in its plastic condition, is passed for a considerable distance over a setting conveyor which gives a time 50 period sufficient to permit the setting of the

5 gypsum. When the gypsum has nearly set, the plaster boards are cut to length, continued along the setting conveyor and then passed through a drying kiln which is usually of the continuous type in the form of an elongated tunnel.

10 Owing to the great length of both the setting conveyor and the drying kiln, it is desirable that the setting conveyor and the drying kiln be positioned parallel to each other in order to conserve 15 floor space and to prevent an abnormally long building. In order to provide such a desirable arrangement of setting conveyor and drying kilns, it is necessary that the board, during its path of travel, double back upon itself to enter the drying kiln. This drying kiln is usually several decks 20 in height so as to further minimize the floor space required. The present invention, therefore, is directed to the point in the apparatus in which the board doubles back on itself, to enter the drying kiln and means are provided for accomplishing 25 this doubling back of the board automatically, and the feeding of the boards into the kiln without manual effort.

30 The automatic doubling back or reversing mechanism for the plaster boards, comprises a framework 10 of any desired shape to properly support the mechanism of the invention, and standards 11, supporting said framework. The plaster boards 12, which have been manufactured as herein above described, pass along the setting 35 conveyor 13, the same being preferably composed of a series of rollers 14, which may be positively driven, if desired, by a mechanism not shown. In lieu of a positive drive for the rollers 14, the setting conveyor 13 may be inclined at an angle 40 to the horizontal as shown in Fig. 2, in which case the plaster boards pass down the conveyor 13 under the influence of gravity. The conveyor 13 is preferably of considerable length so that the 45 plastic material has a chance to set before the boards are cut to desired lengths, and continued 50 in their movements along the conveyor 13.

Near one end of the conveyor 13, is a roller 15 which is rotatably supported at one end of a pair 45 of oppositely disposed arms 16, said arms being pivotally mounted at the other end on pins, 17 secured to the conveyor 13. The roller 15 is provided with a centrally located shaft 18, and a pulley 19 is secured to one end of said shaft, said pulley being operatively connected by a belt 20 to another idler pulley 21 which is rotatably supported by the conveyor 13. A tightener pulley, 22, is mounted to contact with the belt 20, said pulley 22 being rotatably mounted on the end of a pivotally 55 mounted arm 23 so as to maintain a tension

in the rope 20 at all times, and to permit a slight vertical movement of the roller 15. The pulley 21 is secured to a rotatably mounted shaft 24, and a second pulley 25 is also secured to said shaft and is connected by a belt 26 to a suitable source of power such as a speed reducer 27 operatively connected to an electric motor 28.

As the plaster boards 12 travel down the roller conveyor 13 they come into contact with the roller 15, and are driven forwardly by said roller 15, the plaster boards at the same time, raising the roller 15 the thickness of said boards, so as to permit the passage of said boards under the roller 15. The roller 15, thus drives the plaster boards 12 down the conveyor 13 at a uniform speed. As the plaster board 12 continues to move down the conveyor 13 under the action of drive roller 15, it soon makes contact with a series of rollers, 29, said rollers being secured to a shaft 30. The outer ends of shaft 30 are carried in bearing slots 31 formed in a bracket 32, the latter being secured to the conveyor 42 in any suitable way such as by rivets 33. The slot 31 is substantially arcuate in shape so that the shaft 30 can move a limited distance through an arcuate path, this movement of the shaft 30 being controlled by arms 34 pivoted on shaft 21 at one end, and rotatably receiving the shaft 30 at the other end thereof. A pulley 36 secured to the shaft 24, is connected by a belt 37, to a pulley 38 which is secured to the shaft 30, thus causing the rotation of the rollers 29, and the forward movement of the plaster board 12 below said rollers 29. An idler roller 39 is rotatably mounted immediately below the rollers 29, so that the plaster board 12 is firmly held and propelled forwardly between rollers 29 and 39.

After the plaster board 12 passes beyond the rollers 29 and 39, it falls onto a series of idler rollers 41 which are rotatably mounted on a framework 42. The alternate driven rollers 41a are provided near one end with a pulley 44a secured to the shaft 43 on which the roller 41 is mounted. A drive belt 44 passes in friction contact with the pulley 44a and around end pulley 44b and pulley 45. The pulley 45 is secured to a shaft 46 which is mounted immediately below a shaft 47 which carries the roller 39. A friction roller 48 is secured to the outer end of shaft 46 in contact with a friction pulley 49 which is rotatably mounted on the outer end of shaft 47, so that shaft 46 is normally driven by shaft 47, through friction contact between the pulleys 48 and 49. The pulley 49 is normally driven by friction contact with a friction pulley 50 which is secured to the end of shaft 30. The pulley 49 is rotatably mounted on the shaft 47 so that forward movement of the plaster board over the roll 39 does not cause the rotation of the pulley 49. The belt 44 passes over an upper pulley 52 which is rotatably mounted on a stub shaft 53.

When the board starts through the space between rollers 29 and 39, the rollers 29 are elevated and swing on arms 34 about shaft 24 as a pivot. This upward movement of the rolls 29, causes the pulley 50 to contact with pulley 54 secured on the outer end of the stub shaft 53. Thus, when the board is passing through the rolls 29 and 39, the contact of pulley 50 with pulley 54, causes the rolls 41a to be driven in a counter clockwise direction so as to carry the board up the incline formed by said rolls 41. After the board has completely passed the rolls 29 and 39, the pulley 50 is disconnected from the pulley 54, and is then connected with pulley 49 to reverse the motion of belt 44

and rolls 41a to a clockwise direction, so as to cause the board to move downwardly along the incline formed by rolls 41.

As the direction of motion of the board is reversed, the board moves downwardly along rollers 41 onto a series of idler rollers 56 which are rotatably mounted on a tilting conveyor frame 57. The frame 57 is pivotally supported near the top of a standard 11, on a tube 58, which is mounted in bearing bracket 59 secured to said standard 11. Bearing bracket 60 is secured to the tilting frame 57, and is pivotally supported on the ends of tube 58, a collar 61 outside of said bearing 60, serving as a support for a washer 62. A shaft 63 passes through the center of the washer 62 and through the tube 58, said shaft being provided at one end with a laterally extended pin 64, which serves to confine a spring 65 between said pin and the washer 62 so as to normally urge the shaft 63 to the right, as seen in Fig. 6. The mechanism connected with the shaft 63, will be more fully described.

As the plaster boards move downwardly with the rollers, 56, their movement is hastened by causing some of the rollers 56a to be positively driven in a clockwise direction, as seen in Fig. 2. This is accomplished by mounting pulleys 67 on the outer ends of some of the shafts 68 which support said rollers, a drive belt 69 passing over said pulleys, and around an end drive pulley 70. The pulley 70 is mounted upon roller shaft 71, and another pulley 72 is secured to said shaft 71, said pulley 72 being connected by a drive belt 73 to another pulley 74 which is secured to a counter shaft 75. A pulley 76 is also secured to the shaft 75, and is connected by a drive belt 77 to a pulley 78 which is mounted on the shaft of a motor 79, the latter being secured to the underside of framework 57.

As previously pointed out in the description a drying kiln 80 for the plaster board is preferably arranged below or parallel to the setting conveyor 13 so as to conserve floor space. This drying kiln 80 is usually constructed with a plurality of decks which are indicated in this case as A, B, C, and D respectively. Inclined roller conveyors 81 lead to these corresponding kiln decks and convey the plaster board from the lower end 82 of tilting frame 57 to said kiln decks. In order to rock the tilting frame 57 about its pivot 58, so that the lower end 82 thereof, registers with the desired roller conveyor 81, a suitable control mechanism is attached to said framework 57, to shift the position of said framework at the proper instant.

This control mechanism includes lugs 84 secured to the side of framework 57, a connecting rod 85 being pivotally connected at one end to a lug 84, and at the other end to a crank pin 86 secured on a gear wheel 87. A pinion 88 meshes with the gear wheel 87, said pinion being secured to a sleeve 89 which is rotatably mounted on a shaft 90. The sleeve 89 is provided with the usual clutch drum 91, so that when clutch head 92 is frictionally engaged in the drum 91, the pinion 88 will be rotated by the shaft 90. A continuous rotation of the shaft 90 is accomplished in any suitable way, such as by a bevel pinion 93 meshing with a bevel gear 94, the latter being secured to a drive shaft 95 connected to any suitable source of power, not shown.

The clutch head 92 is slidably, but not rotatably mounted relative to the shaft 90, and the usual toggle links 96 are connected between said clutch head 92 and a collar 97. The collar 97 is

provided with an annular groove 88, and pins 89 are provided on the end of a lever 100, so that as the clutch head collar 97 is moved axially of the shaft 90, the lever 100 will be rocked about its pivot pin 101. The lower end of the lever 100 is provided with a laterally extending catch arm 102 which is normally urged by spring 103, to enter one of a plurality of slots 104 formed in the outer periphery of a lock wheel 105, the latter being secured to a shaft 106 to which is secured gear wheel 87. The purpose of the catch arm 102 is to lock the tilting frame 57 so that the lower end thereof will register exactly with the desired roller conveyor 81 which corresponds to the desired deck of the drying kiln.

The operation of the tilting frame 57 is such that the lower end 82 thereof, would be locked opposite the roller conveyor 81 corresponding to say deck A of the drying kiln. The next movement of the tilting frame 57 would bring its lower end 82, opposite roller conveyor of deck B of the drying kiln, and so on, until a board is deposited on each of the roller conveyors 81 which deliver to the drying kiln. A long segment 107 on the disc, 105, then causes the tilting frame 57 to move to the uppermost roller conveyor 81 opposite deck A, ready for a new cycle of operations. This movement of the tilting frame 57 is controlled entirely by the movement of the boards down the rollers 56. A roller 110 is rotatably mounted on the end of a lever 111, the opposite end of said lever being secured to a rock shaft 112 which is rotatably mounted in suitable bearing brackets 113 secured to frame 57. The outer end of shaft 112 is provided with a lever 114, the outer end of which is connected by a rod 115 to a bell crank lever 116. (Fig. 6.) The bell crank lever 116 is pivotally mounted on a pin 117 secured to a bracket 118, the latter being secured to the frame 57. The free end of bell crank lever 116, is provided with a rounding surface 119 which is adapted to contact with the end of shaft 63 so that when said lever 116 is rocked, the shaft 63 will be moved axially. The end of shaft 63 opposite the lever 116, is loosely received in a socket 120 formed on a lever 121, one end of said lever being pivotally mounted on pin 122, the latter being secured to a bracket 123 mounted on the framework of the machine.

50 A connecting rod 124 extends diagonally from the free end of lever 121 to one arm of a bell crank lever 125, (Fig. 5), the latter being pivotally mounted on a bracket 126. The free end of lever 125 is pivotally secured to a rod 127, the latter being pivotally connected to one end of a lever 128 which is pivotally mounted on bracket 126. The free end of lever 128 is provided with a catch shoulder 129 which is adapted to engage the free end of a pawl 130, the latter being pivotally secured to the bracket 126. An arcuate link 131 pivotally connects the pawl 130 to a bell crank lever 132, the latter being pivoted to bracket 126 by pin 132a. The free arm 133 of the lever 132, bears against the collar 97 so that when said lever 132 is moved in a counter clockwise direction, as seen in Fig. 5, the clutch head 92 is frictionally engaged into the clutch drum 91, to cause the rotation of shaft 106, and the movement of tilting frame 57. A spring 135 connected to the end of lever 132, normally tends to urge said lever in a counter clockwise direction, so as to cause the axial movement to the right of the clutch head 92. A crank disc 136 is secured to the end of shaft 106 opposite the gear wheel 87, and is connected by a rod 137 to a lug 138, which

is similar to lug 84, and for the same purpose. A cam 139 is secured to the shaft 90 below the lever 132 so that one rotation of the shaft 90 will cause said cam 139 to raise the lever 132 and thus engage the pawl 130 behind the catch shoulder 129 ready for a new cycle of operations.

In some cases, damaged boards will be produced and it is desirable to separate these and not send them through the drying kiln. For this purpose, a pair of rods 140 are provided with bearings 141 on their lower ends. The upper ends of rods 140 are laterally bent to pivotally engage in slots 142 formed, one on one arm of each of two bell crank levers 143. The levers 143 are pivotally mounted on pin 144 and shaft 145 and their other arms 15 are pivotally connected together by rod 146. A hand lever 147 is secured to the shaft 145 so that the operator may actuate said lever 147 if a damaged board appears, thus preventing the reversal of direction of rollers 41 and causing the damaged board to be moved to the extreme left (Fig. 2) into a container not shown.

In operation, the plaster board 12 moves down the inclined roller conveyor 13 under the action of gravity until it strikes the driven roller 15 which moves upwardly and engages the board, to drive it forwardly at a definite speed. As the board moves forwardly, it engages the roller 29 which also moves upwardly, carrying with it the friction pulley 50 which is moved upwardly a sufficient distance to engage the friction pulley 54 and cause the latter pulley to rotate and drive the belt 44, the latter causing the counter clockwise rotation of rollers 41, as seen in Fig. 7. As the board is delivered from between the rollers 29 and 39, it is carried up the inclined roller conveyor by the rotating rollers 41, and upon leaving said rollers 29 and 39, roller 29 moves downwardly until friction pulley 50 contacts with friction pulley 49, which reverses the motion of belt 44 and rollers 41, so as to reverse the movement of the plaster board and carry same forwardly onto rollers 56, on roller conveyor tilting frame 57.

The rollers 56 are positively driven in a clockwise direction, as seen in Fig. 2, by the belt 69, so that the plaster board moves down the tilting frame 57 until the forward edge of same engages the roller 110, causing said roller to move upwardly about pivot 112. This upward movement of the roller, 110, operates the following mechanism in the order named:—lever 114, rod 115, lever 116, shaft 63, lever 121, rod 124, lever 125, rod 127, lever 128, pawl 130, link 131, lever 132 and lever arm 133, so as to move the clutch head 92 into frictional contact with the clutch drum 91, thus causing the rotation with shaft 90, of pinion 88, gear wheel 87 and shaft 106, so as to operate crank connecting rods 85 and 137. The movement of the clutch head 92 and collar 97, causes the lever 100, to move about pivot 101, so as to release catch arm 102 from the slot 104 in disc 107, this release permitting the shaft 106 to rotate, as hereinabove described. The crank rods 85 and 137, which are pivotally connected to lugs 84 and 138, respectively, on the tilting frame 57, support said tilting frame in exact registry with the desired deck of roller conveyors 81 which lead to the corresponding deck of the drying kiln. One rotation of shaft 90 causes cam 139 to engage lever 132 and restore pawl 130 behind catch shoulder 129 ready for a new cycle of operations. Damaged boards may be discharged to the left (Fig. 2) by manually actuating lever 147. Thus, the plaster boards are successively directed into the desired decks of the drying kiln and the operation of in-

Introducing the plaster board into the drying kiln, on the desired deck, is accomplished automatically and without the need of manual attention.

I would state in conclusion that while the illustrated example constitutes a practical embodiment of my invention, I do not limit myself precisely to the details hereinabove described, since manifestly the same can be considerably varied without departing from the spirit of the invention as defined in the appended claims.

Having thus described my invention, I claim as new, and desire to secure by Letters Patent:—

1. In a machine for the manufacture of plaster boards, a setting conveyor, a movable conveyor frame associated with said setting conveyor, crank means operatively connected to said frame, a drying kiln having a plurality of conveyor decks, and automatic means for actuating said crank means at predetermined intervals so as to cause said frame to deliver a plaster board to a predetermined deck of said drying kiln.
2. In a machine for the manufacture of plaster boards, a setting conveyor, a drying kiln associated with said conveyor, means for automatically transferring a plaster board from said setting conveyor to said drying kiln, and means adapted to be manually actuated so as to separate damaged boards and prevent the entry thereof into said drying kiln.
3. In a machine for the manufacture of plaster boards, a setting conveyor, a roller conveyor adapted to receive plaster boards from said setting conveyor, means for causing the rotation of the rollers in said roller conveyor in one direction during the reception of said plaster board, means for automatically reversing the direction of rota-

tion of said rollers after the plaster board has been delivered from said setting conveyor so as to change the direction of movement of said plaster board, and manually actuated means adapted to prevent the reversal of rotation of said rollers so as to cause the separation of damaged boards.

4. In a machine for the manufacture of plaster boards, a setting conveyor, a roller conveyor, associated with said setting conveyor, a drying kiln associated with said roller conveyor, means for causing the rotation of the rollers in said roller conveyor in one direction during the reception of a plaster board from said setting conveyor, means for automatically reversing the direction of rotation of said rollers so as to cause said boards to be moved in the direction of said kiln, and manually actuated means adapted to prevent the reversal of motion of said rollers to separate damaged boards and prevent the entry thereof into said drying kiln.

5. In a machine for the manufacture of plaster boards, a setting conveyor, a tilting conveyor frame pivotally associated with said setting conveyor, a drying kiln having a plurality of roller conveyor decks, means for rocking said conveyor frame about the pivot thereof, a rotatably mounted disc associated with said conveyor frame, said disc having a plurality of locking grooves around its periphery, catch means adapted to successively engage in the grooves of said disc so as to lock said conveyor frame in successive positions adjacent the decks of said drying kiln and means for unlocking said catch from said disc at predetermined intervals so as to shift said conveyor frame from one deck to a second deck of said kiln.

CARL ABSMEIER.
